UNITED STATES PATENT OFFICE.

FREDERICK GODFREY KAELIN, OF CUTCHOGUE, NEW YORK.

DESIGN FOR A GAME-BOARD.

SPECIFICATION forming part of Design No. 33,767, dated December 18, 1900.

Application filed November 2, 1900. Serial No. 35,294. Term of patent 14 years.

To all whom it may concern:

Be it known that I, FREDERICK GODFREY KAELIN, a citizen of the United States, residing at Cutchogue, in the county of Suffolk and State of New York, have invented and produced a new and original Design for Game-Boards; and I do declare the following to be a full, clear, and exact description of the same, reference being had to the accompanying drawings, forming a part thereof.

My invention relates to a design for game-boards, which is illustrated in the accompanying drawings, in which—

Figure 1 is a plan view, and Fig. 2 a sectional view on the line 2 2.

My design consists of a square board A, the surface of which is divided into squares and sections.

In the center of squares C there is a circular projection D, extending above the surface of the board. A like projection is also provided in the center of the circle E.

On the sides of the board, extending around and forming the pockets F, are narrow strips which project above the surface of the board.

Having thus described my design, what I desire to secure by Letters Patent is—

The design for a game-board, substantially as herein shown and described.

In testimony whereof I affix my signature in the presence of two witnesses.

FREDERICK GODFREY KAELIN.

Witnesses:

S. A. WALTER,
JAMES GENEHAN.
